UNITED STATES PATENT OFFICE.

RICHARD WOODFINE, OF MULLAN, IDAHO.

LOCK.

1,181,050.

Specification of Letters Patent. Patented Apr. 25, 1916.

Application filed October 25, 1915. Serial No. 57,816.

To all whom it may concern:

Be it known that I, RICHARD WOODFINE, a citizen of the United States, residing at Mullan, in the county of Shoshone and State of Idaho, have invented new and useful Improvements in Locks, of which the following is a specification.

This invention relates to improvements in the construction of locks, and an object of the invention is to construct a lock, primarily intended for employment upon warehouses or the like, which, while of a simple and comparatively cheap construction, includes substantially heavy bolts so arranged as to be simultaneously moved in a longitudinal direction toward or away from the keeper, and wherein both the bolts must have their ends entirely withdrawn from the keeper before the door can be opened.

Another object of the invention is to construct a lock including double bolts having teeth or rack bars thereon and which are engaged by a pinion having a barrel thereon for the reception of a key whereby both of the bolts will be simultaneously moved in opposite directions toward or away from the keeper, and also whereby both of the bolts cannot be readily brought into unlocking position except by persons familiar with the working of the device.

With the above and other objects in view, the improvement resides in the construction, combination and arrangement of parts set forth in the following specification and falling within the scope of the appended claims.

In the drawings: Figure 1 is a front elevation illustrating the application of a lock and keeper constructed in accordance with the present invention. Fig. 2 is a sectional view approximately on the line 2—2 of Fig. 1, Fig. 3 is a sectional view approximately on the line 3—3 of Fig. 2. Fig. 4 is a perspective view of the bolt or tumbler for the keeper casing, and Fig. 5 is a similar view of the bolt or tumbler for the lock casing.

In the drawing the stationary member is indicated by the numeral 22 and the movable member by the numeral 23. The keeper 24 is secured upon the stationary member, while the lock casing 25 is secured upon the movable member.

Both the lock and keeper are of a substantially similar formation, the side plates of which may be substantially rectangular, but one of each of said plates is formed with

an approximately semi-circular flange 26, and each of said plates is formed with a peripherally integral block 27 spaced from the flange to provide a semi-cylindrical passage 28 between the block and the flange 26. This passage 28 communicates with suitable openings in the face plate 29, and arranged within each of the passages 28 is a semi-circular bolt member 30. Each of the bolt members 30 is formed upon its opposite sides or faces with ribs 31—31 which are received in suitable grooves 32—32 upon the respective flanges 26 and blocks 27. The grooves 32 are arranged longitudinally upon the flange 26 and the block 27 for the major portion of the length of said flange and block, and the end walls of the grooves provide abutments for the ribs 32 to prevent the bolts 30 being entirely moved out of the passages 28. The bolt member 30 of the lock 25 is provided preferably upon its inner face with teeth 33 and the block 27 of the said lock member 25 is provided with a round depression 34 which communicates with the passage 28 and which is adapted to serve as a pocket for a toothed wheel 35 which meshes with the teeth 33 of the lock bolt 29. The toothed wheel 35 is provided with a stem 36 that has a transverse kerf 37 and which extends through the removable side plate of the lock and which is adapted to receive a suitable key whereby the bolt of the lock may be actuated to contact with and revolve the bolt of the keeper so that one of the ends of the keeper bolt will be received in the groove of the lock bolt and one of the ends of the lock bolt will be received in the keeper casing. The bolt members, it is to be understood, are adapted when in unlocking position to be arranged flush with the face plates 29 of the lock and of the keeper, and it is only when the said bolts are brought to this position that the movable element can be disengaged from the stationary member as will, it is thought, be perfectly understood.

From the above description, taken in connection with the accompanying drawings, the simplicity of the device, as well as the advantages thereof will, it is thought, be perfectly apparent to those skilled in the art to which such invention appertains without further detailed description.

Having thus described the invention, what I claim is:

1. In combination with a lock casing and

- a keeper casing, of a bolt in each of the casings, means for actuating the bolt in the lock casing to bring the ends of the bolt flush with the face plate of the lock casing
5 or to cause the bolt to enter the keeper casing to contact with the bolt therein to bring one end of the last mentioned bolt out of the keeper casing and to within the lock casing.
2. The combination with a lock casing and
10 a keeper casing, of a bolt arranged in each of the casings, each of said casings having their bolt openings arranged to aline when the face plate of the lock casing is brought against the face plate of the keeper casing,
15 the bolt in the lock casing being formed with teeth, a toothed wheel in the said casing engaging with the teeth, a kerfed stem connected with the toothed wheel and projecting through the lock casing whereby when
20 turned to revolve the toothed wheel to bring the ends of the bolt flush with the face plate of the lock casing or to move the bolt to within the keeper casing to cause the same to contact with the bolt in the said keeper casing and to move one end thereof out of the keeper casing into the lock casing.
3. A lock casing and a keeper casing each having a semi-circular passage and the said passages adapted to aline when the lock casing and keeper casing are brought together, a semi-circular bolt in the passage of the lock casing and in the passage of the

keeper casing, and means for actuating the bolt in the lock casing to bring the ends thereof flush with the entrance to the passage or to project one of the ends thereof through the said passage to within the passage in the keeper casing to cause the said bolt to contact with the bolt in the keeper casing and force one end of the last mentioned bolt through the passage of the keeper casing into the passage of the lock casing.

4. A lock casing and a keeper casing each provided with a semi-circular passage which communicate when the casings are brought together, the opposite walls of the passage being formed with central grooves, approximately semi-circular bolts one for the passage of the lock and the other for the keeper casing, each of said bolts having its opposite edges ribbed to be received in the mentioned grooves of the passages, the ribs on one of the bolts being slotted to provide teeth, a toothed wheel in one of the casings engaging with the said teeth, and a stem upon the wheel projecting through the casing.

In testimony whereof I affix my signature in presence of two witnesses.

RICHARD WOODFINE.
